UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

PLATE AND STAKE STRUCTURE FOR GONDOLA CARS.

No. 825,086.

Specification of Letters Patent.

Patented July 3, 1906.

Application filed September 18, 1905. Serial No. 278,985.

To all whom it may concern:

Be it known that I, ETHAN I. DODDS, a citizen of the United States, residing at Pullman, in the county of Cook and State of Illinois, have invented certain new and useful Improvements in Plate and Stake Structures for Gondola Cars, of which the following is a specification.

In order to provide a metallic car with sheet-metal sides or ends and coöperating stakes possessing great strength and a neat appearance, I have invented a car of the gondola type wherein the side or end plates and stakes are integral, the stakes being hollow and pressed out of the planes of the metal sheets. To still further strengthen the structure, if desired, I insert in each hollow stake a bar properly fastened to the side or end of the car. In addition the metal side plates are extended across the ends of the transverse beams of the underframe and are provided with top and bottom flanges which may be integral with the plates or may comprise bars riveted or otherwise secured thereto.

In the accompanying drawings I have illustrated several embodiments of my invention, wherein—

Figure 1 is a plan view, partly in section, of a portion of a gondola car embodying my invention. Fig. 2 is a side elevation of the structure illustrated in Fig. 1. Fig. 3 illustrates a modified form of combined plate and stake. Fig. 4 is a plan view, partly in section, of a portion of a car, showing a modified form of my invention. Fig. 5 is a similar view showing a different modification. Fig. 6 is a vertical transverse section of a car employing side plates with integral tapered stakes. Fig. 7 is a vertical cross-section of a portion of a car, showing a modified construction of top and bottom flanges for the side plates. Fig. 8 is a vertical cross-section of a part of a car, illustrating the use of a bar within the hollow stake; and Fig. 9 is a plan view of a car whose side is shown in section, illustrating a reinforcing-bar within each hollow side stake.

Referring first to Figs. 1 and 2, 10 characterizes the centersill, and 11 the body-bolster. 12 is the floor of the car-body, 13 being the end thereof, and 14 the sides, each of which latter comprises a number of alternate

plain metal sheets 15 in conjunction with alternate metal plates 16, having integral hollow ribs 17 at their ends, the ribbed ends of plates 16 overlapping and being fastened by rivets 18 to the ends of plates 15, as is most clearly shown in Fig. 1. The ribs 17, which comprise the side stakes of the car, are of uniform width, as shown in Figs. 1 and 2; but in Fig. 3 I have illustrated a modified construction wherein each plate 16' is provided with an integral hollow rib 17', tapered in width, plate 16' overlapping plate 15' and being secured thereto by rivets 18'.

In Fig. 4 I have shown another form of my invention, in which each side plate 20 has a hollow rib 21 of uniform width, the ribbed end of each plate overlapping the adjacent plate and being secured thereto by rivets 22. The construction shown in Fig. 5 is similar to that shown in Fig. 4, the only difference being that each hollow rib 21', which comprises the stake, is tapered in width, the plates 20' being fastened to each other by rivets 22' the same as illustrated in Fig. 4.

I have illustrated in Fig. 6 a construction employing channel center sills 23, to which are attached, by means of angle-plates 27, cross-bearers or flying transoms 24, having integral upper and lower flanges 25 and 26, respectively, and integral end flanges 28. Floor-plates 29, having integral flanges 30 at their outer edges fastened to the sides of the car, are secured to the upper flanges of the flying transoms and center sills, a strengthening longitudinal plate 31 being riveted to the floor-plates 29 and to the top flanges of the center sills. Side plates 32 overlap and are riveted to the end flanges of the cross-bearers and are provided with integral tapered ribs or stakes 33, which may be tapered in width or depth, or both, and, if desired, may taper toward both ends of the side plate, as shown in Fig. 6, being deepest opposite the top edges of the transverse beams of the car. Plates 32 may each be provided with a rib similar to the construction shown in Fig. 4, or the alternate plates may each have two ribs at opposite ends, as shown in Fig. 1. The side plates are provided with a coping angle-iron 34, riveted thereto, and with a tension angle-bar 35, secured thereto at or near their lower edges.

The construction illustrated in Fig. 7 is in all respects like that shown in Fig. 6, except that the top and bottom flanges 34' and 35', extended outwardly and inwardly, respectively, are integral with the side plates 32'.

In Figs. 8 and 9 I have shown a still further modification in which reinforcing-bars are inserted in the hollow stakes. In the present instance I have shown such bars T-shaped in cross-section; but it will be obvious that bars of other shape may be employed. These bars 36, which are of uniform transverse dimensions if their corresponding ribs are so formed and which are tapered if the ribs are tapered, are secured by means of rivets 37 passing through their flanges to the inner one of the overlapping side plates 38 and 39, the rib on the outer plate forming the stake 40, fitting neatly about the T-bar, as is most clearly shown in Fig. 9. It will be apparent that such a plate with integral stakes may be used on the sides or ends of the car and that modifications may be made in the construction without departing from the substance of my invention as set forth in the appended claims.

This patent is intended to embrace only so much of the disclosure made herein as is covered by the claims.

30 I claim—

1. In a railway-car, a side or end plate having one or more tapered integral ribs forming one or more car-stakes, substantially as described.
- 35 2. In a railway-car, a side or end plate having one or more hollow tapered integral ribs forming one or more car-stakes, substantially as described.
- 40 3. In a railway-car, a side or end plate having one or more integral ribs tapered both in

width and depth forming one or more car-stakes, substantially as described.

4. In a railway-car, a side or end plate having one or more hollow integral ribs tapered in width and depth toward both ends, said rib 45 or ribs forming one or more car-stakes, substantially as described.

5. In a railway-car, the combination of a side or end plate having a hollow tapered rib, and a tapered bar in said rib, said rib and bar 50 forming a car-stake, substantially as described.

6. In a railway-car, the combination of a side or end plate having an integral hollow tapered rib, and a tapered bar in said rib, 55 said rib and bar forming a car-stake, substantially as described.

7. In a railway-car, the combination of overlapping metallic plates, the overlapping portion of one of said plates having an integral hollow tapered rib, and a bar in said rib secured to the other plate, said rib and bar forming a car-stake, substantially as described.

8. In a railway-car, the combination of 65 overlapping metallic plates, the overlapping portion of the outer plate having an integral hollow rib, a standard-bar in said rib secured to the inner plate, said rib and bar forming a car-stake, substantially as described.

9. In a railway-car, the combination of overlapping side or end plates secured together, the overlapping portion of one of said plates having an integral hollow rib forming a car-stake, substantially as described.

ETHAN I. DODDS.
